RADIO PHONOGRAPH CARRIAGE AND CABINET

John Huarisa, Chicago, Ill., assignor, by mesne assignments, to Advance Engineering Company, Chicago, Ill., a copartnership consisting of L. C. Park, Kenneth Turner, John Huarisa, and J. H. Clippinger

Application October 25, 1940, Serial No. 362,724

9 Claims. (Cl. 179—100.12)

This invention relates to combination radio and phonographic units, and more particularly to units employing an automatic record changer.

Automatic record changers have been employed in connection with phonographs for a number of years. More recently, they have been used quite widely in combination radio and phonograph units. In view of the fact that automatic record changers involve considerable operating mechanism, they are more or less bulky in size. These automatic record changers in combination radio and phonograph units are usually disposed in a relatively deep well in the top of the radio cabinet which is accessible by opening the lid of the radio cabinet. In other instances they are mounted substantially on top of the radio cabinet but beneath a lid having a relatively deep skirt or side wall which conceals the unit when not in use. These arrangements for the most part have either been unsightly in appearance or else not readily accessible to the person who wishes to play the machine.

It is an object of the present invention to provide a novel radio phonograph construction in which the automatic record changer and phonograph unit may be quickly and easily brought to an accessible position, but which may be retracted to a concealed position when not in use.

It is a further object of the present invention to provide a novel radio phonograph carriage and cabinet in which the phonograph unit is mounted on a movable carriage which may be partially withdrawn from the radio cabinet when the phonograph is to be played.

Another object of the present invention is to provide a novel cabinet construction for combination radio and phonograph units in which the phonograph unit is mounted on a slidable carriage which is partially withdrawn from the radio cabinet when one or more doors on the front of the cabinet are opened.

Another and still further object of the present invention is to provide a novel supporting and mounting structure for the turntable and associated mechanism of a phonograph or other record player.

The novel features which I believe to be characteristic of my invention are set forth in particularity in the appended claims. My invention itself, however, both as to its organization and manner of construction, together with further objects and advantages thereof, may best be understood by reference to the following description, taken in connection with the accompanying drawings, in which:

Figure 1 is a front perspective view of a combination radio and phonograph unit;

Figure 2 is a rear elevational view of the combination radio and phonograph unit shown in Figure 1;

Figure 3 is a plan view of the phonograph supporting carriage in its retracted position within the radio cabinet;

Figure 4 is a view similar to Figure 3 but showing the phonograph supporting carriage in its withdrawn position; and,

Figure 5 is a vertical sectional view along the line V—V of Figure 3.

A combination radio and phonograph unit as shown in Figures 1 and 2 of the drawings includes a cabinet 11 which houses an automatic phonograph and record changer unit 12 and a radio 13. The radio 13 is mounted in the upper portion of the cabinet 11 and is equipped with the usual control knobs 14, a dial 15, and a set of push button controls 16. The phonograph and record changer unit 12 is carried below the radio unit 13 partially on and partially within a housing 17 which is arranged to slide out of the cabinet 11 when the two cabinet doors 18 are opened. A power cable 19 to operate the mechanism of the phonograph unit 17 extends from the radio 13 as is shown in Figure 2. The pick up head 20 of the arm 21 is electrically connected to the radio set in the conventional manner through a cable 22.

The phonograph unit 12 as shown includes a turntable 23 having a center spindle 24 over which a stack of records are placed and seated on the automatic record changer arms 25.

Referring now particularly to Figures 3, 4 and 5 of the drawings, it will be seen that the housing or carriage 17 of the phonograph unit 12 is provided with a pair of rollers 26 on each side thereof. The housing or carriage 17 as shown contains the principle operating mechanism of the phonograph and record changer unit.

The rollers 26 ride in a pair of metal channels 27 on opposite sides of the casing or carriage 17 which in turn are carried in wooden crossarms 28 which are channeled out to receive the channel bars 29. These wooden bars 28 are secured to the crossbar 29 at the rear of the cabinet 11 and to the crosspiece 30 at the front of the cabinet. Reinforcing blocks 31 are preferably secured to the rear of the bars 28 and the crossbar 29 in the manner as shown in Figures 3, 4 and 5.

The rollers 26 riding in the metal channel bars

27 provide the necessary support for the casing or carriage 17 of the phonograph and record changer unit 12.

Two guide roller elements 32 depending from the casing 17 ride in a channel bar 33 to prevent lateral shifting of the casing 17. The channel bar 33 is mounted on the rear crossbar 29 and the front crossbar 30 and is suitably secured thereto in any convenient manner.

The doors 18 on the front of the cabinet 11 are mounted on cabinet hinges 34 and are provided with knobs or handles 35, which enables them to be swung open at will. Secured to each door 18 is a rearwardly projecting metal plate 36 which is mounted on the rear face of each door. This rearwardly projecting metal plate 36 is equipped with an upwardly projecting roller element 37 which is free to rotate on the plate 36. In the bottom of the casing 17 there are formed two slots 38 which extend at a slight angle to the front face of the casing 17. The roller element 37 on the plate 36 of the doors 18 extend up and ride in these slots 38. From an examination of Figures 3 and 4 of the drawings it will at once be apparent that as the doors 18 are swung open the casing 17 will be partially withdrawn from within the cabinet 11. Suitable stop means (not shown) are provided to limit the outward movement of the casing 17 and to prevent the front rollers 26 from dropping out of their respective channel tracks 27.

As is clearly shown in Figure 1, the phonograph and record changer unit 12 is withdrawn to a sufficient extent by the opening of the doors 18 to render the turntable readily accessible by the person wishing to operate the machine. In this position a stack of records (not shown) may be placed over the center spindle 24 on the supporting arms 25, and the doors 18 may then be closed and the phonograph unit placed in operation in conjunction with the radio 13.

The particular type of arrangement which has been illustrated and described has been found to be particularly satisfactory since the phonograph and record changer unit may be disposed in the interior of the cabinet 11 in a concealed position during ordinary use of the radio and during actual playing of the phonograph itself, and yet at the same time it may be readily and quickly moved out to an accessible position by simply opening the front doors of the cabinet.

While I have shown a particular embodiment of my invention, it will, of course, be understood that I do not wish to be limited thereto, since many modifications may be made, and I therefore contemplate by the appended claims to cover all such modifications as fall within the true spirit and scope of my invention.

I claim as my invention:

1. In a combination radio phonograph unit, a cabinet having at least one door in the front wall thereof, radio receiving and amplifying means in the upper portion of the cabinet, phonograph reproducing means below said radio means and substantially opposite said door, a carriage upon which said phonograph means is mounted, track means mounted in said cabinet, said carriage being slidably supported and carried in said track means, said carriage having a portion with a slot therein disposed at an angle to the direction of sliding movement of said carriage, and a rearwardly projecting arm on said door, said arm having a roller element disposed to ride in said slot, whereby when said door is opened said carriage is partially withdrawn from said cabinet

to place said phonograph means in an accessible position.

2. An electrically operated phonograph unit comprising a cabinet having a front wall and a rear frame member, a door in the front wall of said cabinet, a pair of tracks mounted in said cabinet and extending between the front wall and the rear frame member, a carriage slidably mounted in said track and arranged to be moved 10 on said track from a position completely within said cabinet to a position partly out of said cabinet through said door, phonograph pick up and record playing means mounted on said carriage, stationary amplifying means mounted in said cabinet and electrically connected to the pick up of said phonograph means through a flexible cable, said carriage having an elongated cam track in substantially a horizontal portion thereof and disposed at an acute angle to the 15 direction of sliding movement of said carriage, and a rearwardly extending arm on said door, said arm having a roller element mounted thereon and extending into said cam slot of said carriage, whereby when said door is opened said carriage is partially withdrawn from said cabinet and when said door is closed said carriage is retracted to a concealed position within said cabinet.

3. A phonograph construction comprising a cabinet having a front wall and a rear frame member, a pair of doors in said front wall mounted for swinging movement about substantially vertical axes, a pair of channel members mounted in said cabinet and extending between said 35 front wall and said rear frame member said channel members being disposed to face each other, phonograph pick up and record playing means including a housing having at least two roller elements projecting laterally from each side of said housing and extending into said channel members, a third channel member in said cabinet disposed below said housing and extending between the front wall and the rear frame member of said cabinet means depending 45 downwardly from said housing into said third channel member for restraining lateral shifting of said housing as said housing rides in said first two channel members, said channel members being positioned in said cabinet to support said 50 housing for movement partially out of said cabinet when said doors are opened, each of said doors having a rearwardly projecting arm thereon, said housing having a pair of elongated slots in the base thereof said slots being disposed so 55 that their longitudinal axes intersect at an imaginary point toward the front of said housing, and roller elements on the arms of said doors which extend into and ride in said slots, whereby when said doors are opened said housing is partially withdrawn from said cabinet.

4. In combination with a radio-phonograph cabinet formed with a recess opening through one side thereof, a platform slidably disposed in said recess and adapted to be slid in and out of the cabinet, a pair of doors hingedly secured to the edges of the recess and arranged to close the opening to the recess, said platform formed with a pair of slideways thereon, said doors having a pair of arms extending inwardly therefrom and members carried by said arms and engaging said platform in said slideways and operable upon opening and closing movement of the doors to slide the platform in and out of the cabinet.

5. In combination with a radio-phonograph cabinet having a recess therein, a platform slid-

able into and out of said recess, a pair of doors hingedly secured to the sides of the opening into said recess for closing the recess, said platform provided with a pair of guideways, arms rigidly carried by said doors and extending inwardly therefrom, lugs disposed on the ends of said arms and extending into said guideways, said lugs adapted to engage the sides of said guideways to exert a pushing and pulling action therein to push the platform into the recess when the doors are closed and pull the platform out of the recess when the doors are opened.

6. In combination with a radio-phonograph cabinet formed with a recess therein opening through a side of the cabinet, a pair of doors secured to the cabinet at the sides of the opening into the recess for opening and closing the opening, a pair of rigid arms secured to the inner sides of the doors and extending inwardly therefrom, a platform for holding a record player slidably disposed therein, a pair of oppositely disposed guideways extending from the sides of the platform toward the center thereof, lugs carried by each of said arms and disposed in said guideways, said doors operable upon opening or closing to cause said lugs engaged in said guideways to pull the platform out and push the platform in, said lugs sliding in said guideways during the movement of the doors and platform to allow for the arcuate movement of said arms.

7. A cabinet for housing a phonograph record player, having a recess therein opening through at least one side of the cabinet, a pair of doors for closing said recess hingedly secured to the cabinet at the sides of the opening to the recess, a platform slidably disposed in said recess, a pair of guideways for said platform extending across the platform from the sides toward the center, each of said doors having a rigid arm secured thereto and movable therewith and extending inwardly therefrom, an abutment carried by each arm and entering into the confines of each of said guideways, said abutments adapted to engage the fronts of said guideways when the doors are being opened to pull the platform out of the cabinet and to engage the backs of said guideways to push the platform back into the cabinet when the doors are closed and said abutments being slidably in said guideways to allow for the arcuate movement of said arms during the opening and closing of said doors.

8. A cabinet of the class described having a

recess therein, opening through a side of the cabinet, a platform for holding a record changer or the like slidably into and out of said recess, a pair of doors for closing the opening into said recess hingedly secured to the cabinet at the sides of the recess, means for sliding the platform in and out of the cabinet upon closing and opening movements of said doors including a pair of arms rigidly secured to the inner surface of said doors and extending inwardly therefrom and adapted to be swung therewith and an upstanding abutment carried by each arm at its end, said platform being provided with a pair of guideways disposed on the underside of the platform and extending from the sides toward the center and adapted to receive said abutments, said abutments adapted to engage the sides of said guideways to pull and push said platform out and into said recess upon opening and closing movement of said doors and said guideways allowing said abutments to slide therein during said opening and closing movements to allow for the arcuate movement of said arm, said arms adapted to support said platform when the platform extends out of the recess.

9. A cabinet of the class described having a recess therein opening through a side thereof, a platform for supporting a record player or the like slidably disposed in said recess, a pair of doors for closing the opening into said recess hingedly connected to the cabinet at the sides of said recess, means for connecting said doors to said platform operable to slide the platform out of and into said recess upon opening and closing of the doors comprising a pair of arms rigidly carried by said doors and extending inwardly therefrom and under said platform, a pair of upwardly extending pins carried by the arms at the ends thereof and rollers disposed in said pins, said platform being provided with a pair of cam ways on the underside thereof, said cam ways being substantially straight and extending from the side of the platform toward the center and being inclined toward the front of the platform, said rollers in said arms being disposed in and slidably in said guideways and operable when the doors are swung to push or pull against the sides of said guideways to push or pull the platform in or out of said cabinet, said arms furnishing a support for said platform when it is slid out of said cabinet.

JOHN HUARISA.
